(57) **CLAIM**

The ornamental design for an electrical charger as shown and described.

DESCRIPTION

FIG. 1 is a front view of an electrical charger showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.
